UNITED STATES PATENT OFFICE

JOSEPH N. DEIBERT, JR., OF BEULAH, NORTH DAKOTA

DEHORNING SAW

Application filed August 6, 1930. Serial No. 473,412

This invention relates to devices for dehorning animals, and the primary object of this invention is to provide an improved dehorning saw that may be readily supported from the neck of the animal to be dehorned.

A still further object of the invention is to provide a dehorning saw which is comparatively simple in construction, and which includes supporting means therefor adjustable 10 for accommodating the neck of various sized animals.

A still further object of the invention is to provide a dehorning saw which may be readily mounted on the neck of various sized 15 animals and which can be manually operated with facility.

Other objects and advantages of the invention will become apparent during a study of the following description taken in connection 20 with the accompanying drawings wherein:

Figure 1 is a side elevational view showing the device as applied to an animal.

Figure 2 is a vertical sectional view there- 25 through,

Figure 3 is a fragmentary end elevational view thereof,

Figure 4 is a top plan view of the saw and associated mechanism,

Figure 5 is a detail sectional view taken substantially on the line 5—5 of Figure 4.

Figure 6 is a fragmentary detail view partly in section and partly in elevation illustrating certain details of construction to be 35 hereinafter more fully referred to.

With reference more in detail to the drawings, it will be seen that I provide a body member including a pair of spaced upper and lower plates 5 and 6 respectively. The plates 40 5 and 6 are retained in spaced assembled relation through the medium of vertical bars 7 that are connected together through the medium of a pair of spaced transverse cross bars 8. Movable relative to the body member, and supported on the lower plate 6 is a 45 horn engaging member 9 that is provided with a longitudinally extending slot 10. The slot 10 at the forward end of the member 50 9 is suitably shaped as at 11 to accommodate

and engage the horns of the animal to be dehorned.

Adjacent the opposite end of the slot, and on opposite side edges of the slot, the plate is provided with rack teeth 12. Meshing with the teeth 12 for imparting the sliding movement to the member 9 relative to the plate 6 is a worm 13. The plate 6 is provided with a suitable opening 14 registering with the slot 10 and accommodating the worm 13. The worm 13 is mounted on a suitable shaft journaled in suitable bearings 15, one beneath the lower edge of each cross member 8. Also mounted on the shaft is a suitable gear wheel 16 that meshes with a gear wheel 17. The gear wheel 17 is mounted on the lower end of a vertical shaft suitably journaled in bearings 18 and 19 on the upper and lower plates 5 and 6. The upper end of the shaft is equipped with a suitable actuating handle 20. Obviously by rotating the handle 20, rotative motion is transmitted to the worm 13 through the gearing just described, and the worm 13 meshing with the teeth 12 will move the horn engaging member 9 relative to the plate 6.

A saw supporting shaft 21 is suitably mounted in a vertical position at the forward end of the plates 5 and 6. Supported on the saw supporting shaft 21 is a suitable disk cutter or dehorning saw 22 that is adapted to rotate in a horizontal plane. Mounted on the shaft 21 adjacent the upper end of the shaft is a pinion 23 that is adapted to rotate in a horizontal plane. The pinion 23 meshes with a relatively large gear wheel 24 that is splined to the shaft supporting the gear 17, and the gear 24 also rotates in a horizontal plane.

From the foregoing then it will be seen 90 that when the end 11 receives therein the horn of the animal to be dehorned, by rotating the handle member 20 in the proper direction, the body member including the plates 5 and 6 will move toward the right 95 in Figure 5, or in a direction toward the horn, while at the same time the saw 22 will be rotated for cutting engagement with the horn.

For supporting the structure shown in 100

Figures 4 and 5, and hereinbefore described in detail, in suitable dehorning position on the animal, I provide a suitable yoke that includes a member 25 that is adapted to extend transversely of the neck of the animal, and to the ends of which are pivoted as at 26 the upper curved end of side members 27 that are adapted to extend downwardly along opposite sides of the animal. Bolted 10 to the curved upper end of one of the side members 27 as at 28 is the lower end of a suitably shaped bracket 29 that has at its upper end a rest or supporting plate 30 provided with upstanding flanges or sides 31. 15 The rest or plate 30 provides a support for slidably supporting the body that includes the plates 5 and 6, the lower plate 6 resting on the rest 30. Hinged to the upper edge of each of the side members 31 is a retaining member 32 that is adapted to overlie and engage the upper plate 5. For retaining the members 32 in engagement with the top plate 35 I provide spring retainers 33. Each of the retainers 33 has one end thereof receivable in a suitable apertured lug 34 formed on the side member 31, and the opposite end thereof adapted to be received in the opening of a suitable lug 35 formed on the member 32 (see Figure 3). 20 For accommodating the neck yoke to various sized necks, each of the side members 27 has disposed in spaced relation thereto an adjusting plate 36 that is adapted to be moved relative to the side member 27 for 25 contact with the adjacent side of the animal. Each of the members 36 has a plurality of ratchet members 37 pivoted thereto as at 38. The member 27 is provided with a plurality of openings for accommodating the ratchet 30 members 37, and the upper edges of the openings 39 are suitably beveled to engage the teeth of the ratchet members 37 for retaining the side member 27 and its member 36 in spaced relation relative to one 40 another and at any desired point of adjustment.

To each of the members 36 there are pivoted preferably four of such ratchet members 37, two of which are arranged in vertical spaced alinement, and the remaining two arranged in horizontal spaced alinement, and the outer ends of the rack members 37 are all connected together, one with the other through the medium of suitable springs 40 as 45 clearly suggested in Figure 1. The springs 40 obviously urge the teeth of the rack members 37 into engagement with the beveled edges of the respective openings 39 (see Figure 6). For detachably connecting the lower 50 ends of the side members 27 there is provided a suitable member 41 that is pivotally connected to the lower end of one of the side members 27 as at 42. The member 41 is 55 adapted to extend under the neck of the animal and has its free end adapted to be

engaged with the free end of the other of the side members 27 in any suitable manner.

For bracing and supporting the yoke in position I provide a brace means which include a cross member 43 that is adapted to extend transversely of the animal at the junction of the back and neck of the animal, and to the ends of this cross member are hingedly connected longitudinally twisted side straps 44 that extend downwardly along the sides of the animal. Adjustably connected to the lower end of each of the side members 44 is a retaining strap 45 that is twisted longitudinally adjacent its lower end to provide an inwardly and rearwardly directed end portion 46 that is adapted to extend underneath the body of the animal on the inner sides of the fore legs of the animal.

Each of the straps 45 adjacent its upper end is provided with a lateral flange 47. The flange 47 is suitably apertured to accommodate a bolt 48 that extends therethrough and also extends through a vertical slot formed in the vertically disposed flange 49 formed on an adjacent side strap 44. The bolt 48 will of course have a suitable nut associated therewith so that by tightening the nut, the side straps 44 and member 45 may be retained in longitudinal adjusted position relative to one another.

The bolts 48 provide pivots for the inner ends of arms 50. Each of the arms 50 comprises a pair of longitudinally adjustable sections 51 and 52 respectively, the section 51 being pivoted through the medium of the bolt 48. The section 51 at its free end is provided with a longitudinally extending slot 53 that at its upper edge is suitably serrated or otherwise formed to provide teeth with which is engaged a pin or bolt 54 carried by the section 52 and operable in the slot 53 for maintaining the sections 51 and 52 in a predetermined longitudinally adjusted position.

At its inner end, the section 52 is provided with a suitable longitudinally extending stop flange 55 for contacting the upper edge of section 51 to retain the sections against pivotal movement with respect to one another in one direction. The section 52 may also be equipped with a suitable handle 56 to facilitate manual adjustment of the sections.

The section 52 of the respective arms 50 has a pin and slot connection 57 with one of the side members 27 which will permit the arms 50 to attain the angular position suggested in Figure 1 when the device is assembled on the animal. The sections 52 of the respective arms 50 at the outer free ends of the sections 52 are respectively equipped with a jaw engaging and supporting head 58 that is adapted to engage the jaw of the animal rearwardly of the ears of the animal.

Links 59 are pivoted at one end to the side straps 44 and at their opposite ends to the side members 27 of the neck yoke, and these

straps 59 may be formed of metal or any other suitable material for bracing the yoke 27 as suggested in Figure 1.

From the foregoing then it will be seen that I have devised a comparatively simple and thoroughly reliable and efficient dehorning device which may be readily supported in dehorning position on the animal, and which when placed on the animal will be suitably braced and retained in position.

Even though I have herein shown and described the preferred embodiment of my invention, it is to be understood that the same is susceptible to changes fully comprehended by the spirit of the invention as described, and the scope of the appended claims.

Having thus described my invention, what I claim as new is:

1. In a dehorning device of the class described, a neck yoke adapted to straddle the neck of the animal, a bracket supported on said neck yoke, horn engaging and sawing means slidably mounted on said bracket, and adjustable brace means embracing the body 25 of the animal and having engagement with the yoke for retaining said yoke in position on said animal and braced with respect to the body of the animal.

2. A dehorning device comprising a body, means engaging said body and adapted to embrace the neck of the animal for supporting and bracing said body adjacent the horn to be severed, a horn engaging member, means operatively connecting said horn engaging member with said body for moving said body and horn engaging member relative to one another when said member is engaging the horn, a saw rotatably mounted on said body for cutting engagement with the horn 40 during relative movement of said body and said horn engaging member, and mechanism for moving said body and said horn engaging member relative to one another simultaneously with the cutting action of said saw.

45 3. A dehorning device comprising in combination a pair of spaced upper and lower plates, a guide bracket for slidably supporting said plates, means for supporting said guide bracket and adapted to embrace the neck of the animal to be dehorned, a horn engaging member mounted between said plates, teeth on said horn engaging member, a rotatably supported worm on one of said plates meshing with said teeth, actuating 50 mechanism for said worm and a horn cutting member mounted between said plates.

40 4. A dehorning device comprising in combination a pair of spaced upper and lower plates, a guide bracket for slidably supporting said plates, a support for said guide bracket adapted to embrace the neck of the animal to be dehorned, a horn engaging member mounted between said plates, teeth on said horn engaging member, a rotatably supported worm on one of said plates meshing with

said teeth, actuating mechanism for said worm and a horn cutting member supported by said plates, and said actuating mechanism including means for actuating said cutting member simultaneously with the rotation of 70 said worm.

5. In a dehorning device of the class described, a supporting bracket having a substantially U-shaped guide integral therewith, adjustable brace means engageable with said

75 bracket and adapted to be supported on the body of the animal for disposing said bracket adjacent the horn to be severed, a body member slidably supported in said guide for sliding movement relative to said guide, 80 means for retaining said body member in slidable position in said guide, a horn engaging member, said horn engaging member provided with a longitudinally extending slot formed in one end for accommodating the 85 horn of the animal, teeth formed on said member at opposite sides of said slot adjacent the opposite end of the latter, a worm rotatably supported on said body member and engaging said teeth for moving said horn engaging member and said body relative to one another and in opposite directions upon rotation of said worm, a saw rotatably mounted on said body member for rotative movement in a horizontal plane, and mechanism 90 for rotating said worm and said saw simultaneously.

6. In a dehorning device of the class described, a supporting bracket having a substantially U-shaped guide integral therewith, 100 adjustable brace means engageable with said bracket and adapted to be supported on the body of the animal for disposing said bracket adjacent the horn to be severed, a body member slidably supported in said guide for sliding movement relative to said guide, 105 means for retaining said body member in slidable position in said guide, a horn engaging member, said horn engaging member provided with a longitudinally extending slot formed in one end for accommodating the 110 horn of the animal, teeth formed on said member at opposite sides of said slot adjacent the opposite end of the latter, a worm rotatably supported on said body member and engaging said teeth for moving said horn 115 engaging member and said body relative to one another and in opposite directions upon rotation of said worm, a saw rotatably mounted on said body member for rotative movement in a horizontal plane, mechanism for 120 rotating said worm and said saw simultaneously, and means for engaging the jaws of the animal for retaining the head of the animal against movement during the dehorning operation.

7. In a dehorning device of the character described, a yoke comprising a plurality of hingedly connected sections adapted to straddle the neck of the animal to be dehorned, 130

horn engaging and cutting means adapted to be supported on said yoke in operative relation to the horn to be severed, a bracket supported on said yoke and having a guide integral therewith for supporting said horn engaging and cutting means, a brace for said yoke adapted to straddle the animal rearwardly of said yoke, said brace including a pair of longitudinally adjustable side members, each of said side members having a lower end portion thereof adapted to extend rearwardly beneath the body of the animal inwardly of the fore legs of the animal, straps connecting the side members of said brace with the side members of said yoke, means for bracing said yoke relative to said brace member.

8. In a dehorning device of the character described, a yoke comprising a plurality of hingedly connected sections adapted to straddle the neck of the animal to be dehorned, horn engaging and cutting means adapted to be supported from said yoke in operative relation to the horn to be severed, a bracket supported on said yoke and having a guide integral therewith for supporting said horn engaging and cutting means, a brace for said yoke adapted to straddle the animal rearwardly of said yoke, said brace including a pair of longitudinally adjustable side members, each of said side members having a lower end portion thereof adapted to extend rearwardly beneath the body of the animal inwardly of the fore legs of the animal, straps connecting the side members of said brace with the side members of said yoke, means for bracing said yoke relative to said brace member, a longitudinally adjustable arm pivotally carried by each of the side members of said brace, said arms respectively adjacent their free end having pin and slot connections with the respective side members of said yoke, jaw engaging heads on the outer end of said arms.

45. In testimony whereof I affix my signature.
JOSEPH N. DEIBERT, Jr.
